AUGUST D. NEWMAN, OF CANGAI, NEW SOUTH WALES, AUSTRALIA.

KEYLESS LOCK.

1,249,460.

Specification of Letters Patent. Patented Dec. 11, 1917.

Application filed May 31, 1917. Serial No. 172,024.

To all whom it may concern:

Be it known that I, AUGUST D. NEWMAN, a subject of the King of Great Britain, residing at Cangai, New South Wales, Australia, have invented certain new and useful Improvements in Keyless Locks, of which the following is a specification.

This invention relates generally to locks, and particularly to keyless padlocks.

10 The primary object of the invention is to provide a lock which is constructed in such manner as to be positive in both its locking and unlocking operations, and which can not be readily opened by unauthorized persons.

15 A further object is to provide a lock of this character which has its shackle holding mechanism wholly confined within the casing, and which affords no opportunity for tampering with or "picking" the same. A

20 still further object is to provide a lock of this character, which requires a plurality of movements of its actuating mechanism before the shackle holding bolt can be operated to release the shackle.

25 Still further objects reside in providing a lock of this character which is of simple and inexpensive construction, which is composed of but few readily assembled parts, all so constructed and assembled as to minimize 30 the opportunity for wear, breakage, or derangement, which is easy of operation to those familiar with the peculiar characteristics of the lock, and which will prove thoroughly efficient and durable in use.

35 With these objects in view, together with others which will appear as the description proceeds, the invention resides in the novel formation, combination, and arrangement of parts, all as will be described more fully 40 hereinafter, illustrated in the drawings, and particularly pointed out in the claims.

In the drawings:

Figure 1 is a side elevation of a lock constructed in accordance with the invention;

45 Fig. 2 is a sectional view taken longitudinally through the lock, and illustrating the same in locked position;

Fig. 3 is an enlarged longitudinal sectional view taken through the lock and illustrating 50 the parts moved to unlocking position;

Fig. 4 is a bottom plan view of the lock;

Fig. 5 is a sectional view taken on line 5—5 of Fig. 2; and

Fig. 6 is a sectional view taken substantially upon line 6—6 of Fig. 3, the view illustrating the lock on a reduced scale.

Referring now more particularly to the drawings, 7 indicates the lock casing, which may be formed of thin sheet metal, and may be closed at one side by a plate 8. The upper end of the casing is provided with a locking shackle 9, the latter being pivoted to the lock casing at one end as at 10, and being adapted at its opposite end to extend through the opening 11 to the interior of the case, as shown in Fig. 2. The free end of the shackle is provided with an opening as shown, through which a shackle locking tooth or prong is adapted to extend. The particular shape, size, and construction of 70 the casing and shackle is immaterial, and it will be understood that numerous variations in the above detailed construction may, if desired, be resorted to.

The bolt for locking the shackle is indicated at 12, and comprises an elongated member pivoted intermediate its ends as at 13 to the interior of the lock casing as shown, and having its extremities terminate a short distance inwardly from the upper and lower 80 ends of the said casing. The uppermost end of the bolt is provided with a laterally disposed locking tooth or prong 14, which is adapted to project through the opening in the free end of the shackle 9. When the 85 lever is swung upon its pivot in one direction, the prong will extend through the shackle opening, but when the said lever is rocked in the reverse direction, the said prong will be withdrawn from holding 90 engagement with the shackle, whereupon the latter may be swung upon its hinge to open position.

The means for holding the bolt in locking and unlocking position, and also for moving 95 the bolt to such positions, comprises a frame indicated generally at 15. This frame is arranged within the casing so as to be partially withdrawn therefrom and so as to be capable of oscillating or rotating within the casing. The frame includes a central shaft or rod 16, which in the present instance, is hollow, and is substantially equal in length to the length 100 of the casing. This rod extends through an opening formed in a laterally disposed supporting bar 17 affixed to the casing and upon the interior thereof, and extends at its lower end through an opening formed in the base or lower end of the lock casing. The frame 105 also includes a bar 18, carried by the rod 16, but disposed in spaced parallel relation thereto. This bar has a pair of spaced arms 110

19 and 20, by means of which the said bar is secured to the central rod or shaft 16. Screws, rivets or bolts 21 may be employed to connect the arms to the said rod. The 5 lower end of the bar 18 terminates in substantially the same plane with the corresponding end of the rod 16, and the said bar extends through an arcuate slot 22 in the base of the lock casing. A disk or thumb 10 wheel 23 is connected to the lower ends of the rod and bar 16 and 18 respectively, and this disk is preferably of a diameter greater than the width of the base of the lock casing.

The lowermost end of the bolt 12 is provided with a pair of outwardly projecting space studs 24, between which the bar 18 extends, and it is apparent from the foregoing description that upon rotating the thumb disk 23, the frame 15 will oscillate, and such 20 oscillation will cause the shackle locking bolt 12 to move accordingly. This movement will cause the prong 14 to move into or out of locking engagement with the shackle end according to the direction or degree of 25 oscillation of the frame 15.

Pivoted at its inner end as at 25 to the outermost extremity of the arm 19 is a lever 26. This lever extends through a hollow portion formed adjacent the outer end of 30 the arm 20, and protrudes at its lower end through an arcuate slot 27 formed in the base of the lock casing. It will be observed that this lever is disposed normally in spaced parallel relation to both the rod 16 and bar 35 18, and is positioned diametrically opposite to the said bar. A spring 28 normally forces the lever outwardly, and the extremities of the arcuate slot 27 are notched as at 29 and 30. When the frame has been moved to the 40 limit of its rotation in one direction, the lever 26 under impulse of the spring 28 will engage adjacent its lowermost end within one or the other of the notches 29 and 30. The frame will then be locked either in locking 45 or unlocking position as is obvious.

In addition to the rotary or oscillatory movement required for moving the locking bolt to operative or inoperative position, sliding or longitudinal movement is essential. The inner end of the shaft or rod 16 is adapted, when the frame is moved to the limit of its inward movement, to engage behind an outwardly projecting member or arm 31 on the upper end of the locking bolt 12. When in this position, see Fig. 2, it is 55 obvious that oscillatory movement of the frame can not operate to retract the locking prong. This sliding movement of the frame is caused by exerting either inward or outward pressure upon the thumb disk 23, and a spring 32 carried by the central shaft or rod 16 yieldably maintains the said rod in either inward or outward position. It 60 will be observed, particularly with reference to Fig. 3 of the drawings, that the spring 65

32 engages at its oppositely extending portions with the transverse bar 17, maintaining the frame yieldably in either outward or inward position.

In operation, assuming the parts to be in 70 locked position, as shown in Figs. 1 and 2, the disk 23 is pulled outwardly. The tension of the spring 32 is such as will retard the frame against ready movement but may be easily overcome by exerting sufficient 75 pressure. When moved to the position shown in Fig. 3, the innermost end of the rod 16 will be withdrawn from the path of travel of the arm 31 at the uppermost end of the lock bolt, and rotary movement applied to the frame through the thumb disk 23 will rock the said bolt to withdraw the spring 14 from engagement with the free end of the shackle 9. However, the frame is locked against rotation by reason of the 80 spring pressed lever 26 being engaged within the notch 30. It is therefore necessary to depress the lowermost end of the lever 26 to disengage the same from the notch 30, whereupon the frame may be oscillated so as 85 to rock the bolt 12 to withdraw the prong 14 from engagement with the shackle end. When the frame has been turned to the limit of its releasing movement, the lever 26 will lock within the notch 29 in the wall of the 90 slot 27, and should it be desired to prevent tampering with the lock when thus unlocked, inward pressure applied to the disk 23 will cause the frame to move inwardly so that the extremity of the rod 16 will lock 95 behind the arm 31 but prevent swinging movement of the lock bolt.

From the foregoing, it is obvious that I have provided an extremely simple and yet thoroughly efficient keyless lock. It will be 100 observed, particularly with reference to Fig. 4 of the drawings, that a slot is provided in the central portion of the disk 23, but this slot is nothing more than a "dummy" or "blind" to confuse or mislead persons tampering with the lock into believing the lock 105 to be one of the key actuated class.

While the present disclosure is that of what I believe to be the preferred embodiment of the invention, it is to be understood 110 that the invention is not limited thereto, but that various changes may be made in the construction, arrangement and proportion of parts, without departing from the spirit of the invention, as defined in the appended 115 claims.

What is claimed is:—

1. A lock including a casing and shackle, a shackle locking bolt, a frame slidably and 120 rotatably arranged within said casing and adapted when oscillated to move said bolt, and a lever for holding said frame against rotation.

2. A lock including a casing and shackle, a locking bolt adapted to retain said shackle, 125

- a sliding frame mounted for oscillation within said casing, the said frame being connected with said bolt and adapted when rotated to move said bolt, means for holding said frame against rotation, and the said frame preventing movement of said bolt except when moved outwardly of said casing.
3. A lock including a casing and shackle, a shackle locking bolt in said casing, a frame slidably and rotatably mounted in said casing, the said frame being adapted when withdrawn and rotated to move said bolt, means for locking said frame against rotation, and means for yieldably holding said frame against withdrawal.
4. A lock including a casing and shackle, a shackle locking bolt in said casing, a frame slidably mounted in said casing and normally holding said bolt against movement, the said bolt being released when said frame is withdrawn from said casing, and a spring for yieldably holding said frame both in inward and outward positions.
5. A lock including a casing and shackle, a locking bolt pivoted in said casing and being adapted to engage at one end with said shackle, a pair of studs at the opposite end of said bolt and being arranged in spaced relation, a frame rotatably mounted in said casing, a bar on said frame interposed between said studs, and means for holding said frame against rotation.
6. A lock including a casing and shackle, a locking bolt pivoted in said casing and being adapted to engage at one end with said shackle, a pair of studs at the opposite end of said bolt and being arranged in
- spaced relation, a frame rotatably mounted in said casing, a bar on said frame engaged between said studs, and a depressible lever on said frame for holding said frame against rotation.
7. A lock including a casing and shackle, a locking bolt in said casing, a frame slidably and rotatably mounted in said casing and protruding at one end beyond the latter, an arm on one end of said locking bolt, the said frame being adapted when at the limit of its inward movement to engage behind said arm to prevent movement of said bolt, means for holding said frame in inward position, and a connection between said bolt and said frame.
8. A lock including a casing and shackle, a locking bolt pivoted intermediate its ends within said casing, a prong on one end of said bolt, an arm on said bolt end, a pair of studs on the opposite end of said bolt, a frame slidably and rotatably mounted in said casing and protruding at one end beyond the latter, a bar carried by said frame, and being engaged between said studs, a rod adapted when said frame is at the limit of its inward movement to engage behind said arm, a lever pivoted to said frame and protruding beyond said casing, the said casing having an arcuate slot to accommodate said lever, and the said slot communicating at its ends with notches.

In testimony whereof I affix my signature in presence of two witnesses.
